UNITED STATES PATENT OFFICE.

ROBERT C. ALLEN, OF SWARTHMORE, PENNSYLVANIA, ASSIGNOR TO WESTINGHOUSE ELECTRIC & MANUFACTURING COMPANY, A CORPORATION OF PENNSYLVANIA.

COMPOUND-TURBINE ARRANGEMENT.

Application filed April 19, 1927. Serial No. 185,008.

My invention relates to an elastic fluid turbine arrangement, particularly to the arrangement of an elastic fluid turbine of large capacity and using high initial pressure, and 5 it has for its object to provide a practical, efficient and economical arrangement of the elements thereof.

Another object is to provide an arrangement having sufficient low pressure blading 10 to completely expand the large quantities of elastic fluid.

In order to obtain greater efficiencies it has become the practice in turbine engineering to increase the capacity of the turbines and also 15 to increase the initial pressure of the motive fluid admitted to the turbine. This fluid is then expanded to a high vacuum in order to extract all the available power. As the volume of the fluid becomes tremendous at the 20 lower pressures, the problem is presented of providing sufficient low pressure blading to completely extract all the available power.

In accordance with my invention, I provide a high pressure turbine element, an intermediate pressure turbine element and a low pressure turbine element. The motive fluid is admitted at high initial pressure to the high pressure element; and, upon being discharged therefrom, it is admitted to the intermediate 25 pressure element. In the intermediate pressure element, the flow of motive fluid is divided, a portion thereof being passed in one direction through blading which expands it completely to a vacuum, and the remaining portion thereof being passed in the opposite direction but only partly expanded therein. The latter portion is discharged from the intermediate element and passed to the low pressure turbine element in which it again 30 divides and flows in opposite directions to vacuum.

Referring to the drawing for illustration of one embodiment of my invention:

The single figure shows an arrangement of 35 turbine elements in accordance with my invention.

Referring to the drawing in detail, I show a high pressure turbine element 10, an intermediate pressure turbine element 11 and a 40 low pressure turbine element 12, each turbine element being provided with a separate casing. The high pressure element 10 is coupled to and drives an electrical generator 13, while

the intermediate pressure and the low pressure elements are coupled in tandem and drive 55 another electrical generator 14.

The high pressure turbine element 10 consists of a casing 15 and a rotor 16 carried by a shaft 17. High pressure steam is supplied from a conduit 18 and admitted to the turbine 60 by any suitable control means such as a valve 19, which may be governor operated. The steam admitted to the turbine is expanded through blading carried by the casing and the rotor, and discharged through the outlet passage 20.

The intermediate pressure turbine element 11 includes a casing 21 and a rotor 22 mounted on a shaft 23, rotating in suitable bearings. The casing and the rotor carry cooperating 70 rows of blades of any suitable design. The turbine element 11 is of the double-flow type comprising two flow sections 24 and 25. The casing is provided with an inlet passage 26 disposed intermediate the sections 24 and 25, 75 and communicating with said sections. A conduit 20' provides communication between the outlet passage 20 of the high pressure element and the inlet passage 26 of the intermediate pressure element. A reheater 30 is 80 preferably interposed in the conduit 20 for reheating the steam transmitted to the turbine element 11.

Communicating with the exhaust end of the section 24 are two vertical condensers 27 85 for receiving the motive fluid flowing therethrough. The blading in section 24 is designed to completely expand the motive fluid flowing therethrough from the pressure at which it is received therein completely to a vacuum, for example, of about 29 inches. The section 24 is further designed to receive approximately one-third of the motive fluid received from the high pressure turbine element.

The section 25 includes blading which is designed to only partly expand the remaining two-thirds of the motive fluid admitted to the intermediate pressure element, being designed, for example, to expand the fluid 100 to a pressure of eight pounds gauge. The motive fluid flowing through this section is discharged through a passage 28.

The low pressure turbine element is preferably also of the double-flow type and comprises a casing 30 and a rotor 31' carried by 105

a shaft 32'. This element comprises two sections 31 and 32 intermediate which is an inlet passage 33. The inlet passage 33 communicates with the discharge passage 28 of 5 the intermediate pressure element by the conduit 34. In the low pressure element each section receives one-half of the motive fluid admitted to said element, or one-third of the original flow from the high pressure element. 10 Each section is designed to completely expand its portion of the fluid to a vacuum of, for example, 29 inches. The outer ends of the sections 31 and 32 are provided with outlet connections 35 and 36, communicating 15 with the condensers 37 and 38 respectively.

A coupling 40 is provided for connecting the shaft 17 of the high pressure element directly to the shaft 41 of the generator 13. The shafts 23 and 32' of the intermediate pressure 20 and low pressure elements respectively are directly connected by the coupling 42, and the latter shaft is directly connected to the shaft 43 of the generator 14 by a coupling 44.

It is apparent, of course, that the generators are merely given as an example of driven machine, and that the turbine elements may be used to drive any type or types of driven machine. Also, the coupling of the intermediate pressure and the low pressure 30 elements in tandem is only one desirable, though not essential, arrangement.

The operation of the turbine arrangement is as follows: Steam or other motive fluid is supplied to the high pressure element 10 at a pressure of, for example, 500 pounds per square inch, the admission being controlled in any suitable manner by a valve 19. The high pressure turbine element extracts power from the steam flowing therethrough, reducing the pressure thereof, for example, to 40 pounds per square inch, gauge.

This motive fluid is then conducted through the conduit 20 to the inlet 26 of the intermediate pressure element where it is divided, one-third passing through the section 24 and being completely expanded therein. The remaining two-thirds flows through the section 25 and is partly expanded to an intermediate pressure, for example, 8 pounds per square inch, gauge. It is then passed to the inlet 33 of the low pressure element.

In the low pressure element the steam is again divided and flows in equal portions to the sections 31 and 32, each section receiving one-third of the steam discharged by the high pressure element. Each low pressure section completely expands the motive fluid flowing therethrough and communicates with one pair of the condensers 37, 38, which receives 55 the expanded motive fluid and condenses the same.

From the above description it will be seen that I have provided a turbine arrangement wherein motive fluid is expanded from a very 60 high pressure and in which there are three

low pressure ends and condensers for efficiently and completely expanding the motive fluid.

While I have shown my invention in one form, it will be obvious to those skilled in the art that it is not so limited, but is susceptible of various changes and modifications, without departing from the spirit thereof, and I desire, therefore, that only such limitations shall be placed thereupon as are imposed by the prior art or as are specifically set forth in the appended claims.

What I claim is:

1. In a compound-turbine arrangement, a high-pressure turbine element having inlet and outlet openings, a divided flow intermediate pressure turbine element having an inlet opening communicating with the outlet opening of the high-pressure element, said intermediate element including a section for expanding a portion of the motive fluid received through said inlet opening to vacuum and another section for partially expanding another portion thereof, a discharge opening 80 communicating with the second-mentioned section, and a divided flow low-pressure element having an inlet opening communicating with the discharge opening of the intermediate pressure turbine element, said low-pressure turbine element completely expanding 85 all the motive fluid admitted thereto to vacuum.

2. In a compound turbine, the combination of a high-pressure element, a double flow intermediate pressure element comprising 100 two sections both receiving motive fluid from the high-pressure element, the section receiving the flow in one direction completely expanding the motive fluid flowing therethrough to vacuum and the section receiving the flow in the other direction partially expanding the motive fluid flowing therethrough, and a double flow low-pressure turbine element receiving motive fluid from the last-mentioned section of the intermediate 105 pressure element and completely expanding said fluid to vacuum.

3. In a compound turbine, the combination of a turbine element comprising two sections receiving motive fluid at the same pressure, 110 one section completely expanding the motive fluid flowing therethrough to vacuum and the other section partially expanding the motive fluid flowing therethrough, and a second turbine element receiving the motive fluid discharged from the last-mentioned section and completely expanding said motive fluid to vacuum.

4. In a compound turbine arrangement, 115 the combination of a high-pressure turbine element partially expanding the motive fluid flowing therethrough, a driven machine coupled directly to said high-pressure element, 120 a double flow intermediate pressure turbine element comprising two flow sections each 125

receiving motive fluid discharged from the high-pressure element, one section completely expanding motive fluid flowing therethrough to a vacuum and the other flow section partly expanding the motive fluid flowing therethrough, a condenser communicating with the first-mentioned section, a double flow low-pressure element receiving the motive fluid discharged from the last-mentioned section and completely expanding said motive fluid to vacuum, a condenser communicating with each flow section of the low-pressure turbine element, said intermediate pressure and low-pressure elements being directly coupled to each other, and a second driven machine directly coupled to one of the last-mentioned turbine elements.

5. In a compound-turbine arrangement, a high-pressure turbine element having inlet and outlet openings, a double flow intermediate pressure turbine element having an inlet opening communicating with the outlet opening of the high-pressure element, said intermediate element including a section for 20 expanding a portion of the motive fluid received from the high-pressure element and flowing in one direction to vacuum and another section for partially expanding the portion flowing in the other direction, a discharge opening communicating with the second-mentioned section, and a low-pressure element having an inlet opening communi-

cating with the discharge opening of the intermediate pressure turbine element.

6. In a compound turbine, the combination 35 of a double flow turbine element comprising two sections receiving motive fluid at the same pressure and through which motive fluid flows in opposite directions, one section completely expanding the motive fluid flowing therethrough to vacuum and the other section partially expanding the motive fluid flowing therethrough, and a second turbine element receiving the motive fluid discharged from the last-mentioned section and completely expanding said motive fluid to 40 vacuum.

7. In a compound-turbine arrangement, the combination of a high-pressure turbine element, an intermediate-pressure turbine 50 element comprising two sections each receiving motive fluid from the high-pressure element, one of said sections completely expanding motive fluid flowing therethrough to a vacuum and another of said sections partially expanding the motive fluid flowing therethrough, and a low-pressure turbine element receiving partially expanded motive fluid from said last-mentioned section and completely expanding the same.

In testimony whereof, I have hereunto subscribed my name this eleventh day of April, 1927.

ROBERT C. ALLEN.
